INFANT'S FEEDING DEVICE

Stephen Baracate, Troy, N. Y.

Application August 2, 1952, Serial No. 302,341

6 Claims. (Cl. 128—252)

1

This invention has to do with an improved type of infant nursing device. More particularly, it relates to such a device in which the flow of liquid food from the nursing bottle to which it is attachable is valve controlled, having particular reference to valve means which additionally controls the passage of air, thereby tending to eliminate infant colic; and the provision of such a device is a principal object of the invention.

Conventional nursing devices employ rubber or resilient plastic nipples. When no proper air vent is employed with such nipples, infant colic almost inevitably results, depending largely upon the resilient characteristics of the nipple. This is so because some nipples when new are more resilient than others, that is to say, relatively "soft" or "hard." Primarily, however, all nipples after a period of use become soft or lose, to a certain extent, their necessary resiliency characteristics. For this apparent reason they tend to collapse during use after a substantial amount of the milk in the bottle has been withdrawn because of the resulting vacuum that is created in the bottle. Consequently, air is by-passed along the sides of the collapsed nipple into the oral cavity and infant colic results. It is significant that such rubber type nipples vary in their resiliency characteristics when new, and all ultimately decline or deteriorate as to such characteristics during use so that they can never be said to be constant or reliable in this connection. Too often, it would seem, cures for infant colic have been prescribed when the proper cure in this respect would better be the removal of the cause, namely, the conventional resilient rubber type nipple.

It has long been recognized that it would be a distinct advantage to overcome this problem of infant colic, and this has now been accomplished by means of the present invention.

Generally, therefore, it is also an object of the invention to overcome the foregoing difficulties and disadvantages and to provide an infant's feeding device that is simple of construction, economic of manufacture, as readily and easily useable as conventional devices, if not more so, and positive in operation.

More specifically, it is an object of the invention to provide such a device involving a casing adapted to be applied to the open neck of a nursing bottle with a non-collapsible nipple connected to the casing, an extension on the nipple adapted to project into the bottle in the neck area or a short distance therebeyond, the extension having a longitudinal passageway therethrough as well as through the nipple, and valve means mounted

2

on the extension and communicating with the passageway, the same being so constructed and arranged that the valve will be submerged in the liquid food, or milk, when the bottle is up-ended and will remain so submerged until the bottle has been substantially completely emptied.

Other specific objects of the invention are the provision of such a device in which the valve means is eccentrically mounted and preferably weighted such as, for example, by a ball check element, or other suitable means, to be suspended in submerged position at all times within the liquid food; in which the device may be used in conjunction with a nursing bottle having an air valve means, preferably located in the bottom of a bottle; in which a supplemental valve means is utilized preferably associated or cooperatively connected with the extension member and the nipple, the latter members being relatively movable with respect to each other, whereby to control the flow of milk and air from the bottle through the nipple; in which, in this latter connection, the valve means includes a secondary needle type of valve projecting through the nipple, which nipple is provided with a valve seat to receive the same around the outlet port of the nipple; and wherein the nipple and casing are provided with correlated indicia to indicate the open and shut position of the combined liquid and air valve means.

Other objects of the invention will in part be obvious and will in part appear hereinafter.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention reference should be had to the following detailed description taken in connection with the accompanying drawings, in which:

Fig. 1 is a side elevational view of one modification of the device attached to a nursing bottle, and in a partly up-ended position for use;

Fig. 2 is a sectional view through the bottom of the nursing bottle illustrating an air valve means preferably usable with the device;

Fig. 3 is a transverse sectional view of one form of the device attached to the open end of the nursing bottle;

Fig. 4 is a transverse sectional view of the liquid control valve taken along the lines 4—4 of Fig. 3;

Fig. 5 is a side elevational view of a fragment

tary portion of another form of the invention;

Fig. 6 is a perspective view of Fig. 5, on a somewhat smaller scale, illustrating valve control indicia on the casing and nipple;

Fig. 7 is a sectional transverse view of Fig. 5 illustrating the relatively movable nipple and secondary valve means in opened position;

Fig. 8 is a transverse sectional view of Fig. 7 taken along the lines 8—8 of Fig. 7; and

Fig. 9 is a transverse sectional detail view, somewhat enlarged, of a portion of Fig. 7 illustrating the relatively movable nipple and secondary valve means in closed position.

Referring now more particularly to the drawings there is indicated generally at 10 one form of the device attached to an infant's nursing bottle 11 having a screw-threaded open neck 12. This device comprises an internally threaded casing 13 adapted to be applied to the neck 12 against a washer, or gasket 14.

Connected to the casing is a non-collapsible nipple 15 which may be made of any suitable non-resilient material in the form of any desirable substance, preferably of a plastic. This nipple may be solid, as shown in the drawing, or hollow. An extension 16 on the nipple, of suitable length is adapted to project into the neck of the bottle but terminating short of, or marginally inwardly, of the open neck. A narrow passageway 17 extends longitudinally of the nipple and through the extension 16 to one or more transverse openings 18. An annular groove indicated generally at 19 surrounds these openings.

Eccentrically mounted on the end of the extension 16 is a liquid flow control valve indicated generally at 20. This constitutes a cylindrical member 21 which is held in position by a set screw 22 having a lug thereon which loosely fits into the groove 19 to hold the valve rotatably positioned on the extension or shaft 16. A small opening 23 is drilled into the bottom of the cylinder 21 and communicates with a central bore 24 therein. Loosely movable within this bore is a ball check valve element 25.

In operation, the bottle 11, when up-ended, will cause the milk to fill the entire neck area and the ball check valve will always be pulled into downward position because of its eccentric mounting aided by the weight of the ball so that it will always be submerged in the milk remaining in the bottle. While a vacuum may occur due to the withdrawal of the milk it will be obvious that there can be no danger of collapse of this type of nipple. However, I prefer to employ an air vent in the bottom of the bottle as illustrated generally at 26. This vent comprises a cylindrical extension 27 having one or more openings 28 communicating with the bore 29 therein. The cylinder 27 is sealed on the inside as shown at 30 and the open end of the bore is closed by a plug 31 having a longitudinal opening 32 therethrough communicating with the bore 29. The bottom of the bottle, of course, may be countersunk so that the plug 31 is flush therewith. When the bottle is in vertical position a ball 32 in the bore 29 will cause it to seal the opening 32 in the plug 31 by overlying the opening 32 as shown by the dotted line position of the ball 32'. When the bottle 11 is up-ended air will be permitted to rush through the opening 32 and through the openings 28, the ball 32' having fallen to an out of the way position against the sealed end 30 of the cylinder 27.

In the form of the invention shown in Figs. 5 through 9, I employ the same type of casing, bottle and valve means above described and no further description is considered necessary in this case. However, a secondary valve means indicated generally at 33 is employed completely to shut off the flow of milk, and of more importance, to shut off the flow of air through the nipple when all, or substantially all, of the milk has been withdrawn from the bottle as will more fully appear hereinafter.

The secondary valve means is provided by an arm or disk member 34 on the extension 16 as indicated in Figs. 7, 8 and 9 of the drawings. A slotted opening 35 in the arm 34 receives a pin 36 secured in the casing 13. A small diameter hole longitudinally drilled through this pin will provide an air vent for the device. Adjacent the member 34 the extension 16 is threaded as at 37 and the nipple 38 at its base is correspondingly threaded to receive the threaded portion 37 of the extension 16. Preferably, the nipple is hollow as shown in the drawing and is also made of a non-resilient or non-collapsible, that is, hard material such as plastic. The extension 16 beyond its threaded portion extends into the nipple in the form of a needle as at 39 and is adapted to engage the open, or outlet end, of the nipple in a seat 40 provided therefor. The needle 39 has a longitudinal passage therethrough as at 41 and this extends through the extension portion 16 where it also communicates with radial or transverse openings 42 to communicate with the valve 20. The needle is tapered at its end so that it will properly seat in the end of the nipple and at this point is also provided with a plurality of passages 43 for the passage of liquid therethrough and through the nipple when the needle and seat are separated. This separation operation is accomplished by giving the nipple, which is rotatably mounted in the casing, a slight rotational movement whereupon it moves away from the arm or disk 34 as shown in Fig. 7, other than a slight rotation to right or left being determined by the pin 36. When the nipple is moved slightly in the opposite direction it moves against the arm 34 and the needle becomes seated in the end of the nipple to prevent passage of milk, and more important still, air through the end of the nipple. In order to determine whether the secondary valve means 33 is opened or closed, indicia indicated generally at 44 is provided on the casing and nipple as shown in Fig. 6.

It will thus be seen that the objects hereinbefore set forth may readily and efficiently be attained and since certain changes may be made in the above article and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention what I claim as new and desire to secure by Letters Patent is:

1. In an infant nursing device, the improvement comprising the combination of a casing adapted to be applied to the open neck of a nursing bottle containing a liquid food; a non-coll-

5

lapsible nipple connected to said casing; an extension on said nipple adapted to project into said bottle but terminating marginally inwardly of said open neck, and having a longitudinal passageway therethrough and through said nipple; valve means, communicating with said passageway, mounted on said extension adjacent said open neck in a manner such that the valve will be submerged in said liquid food when said bottle is up-ended and will remain so submerged until said bottle has been substantially completely emptied; and valve means on said extension, cooperatively associating said extension and said nipple, said means and said nipple being relatively movable with respect to each other, whereby to control the flow of liquid food and air from said bottle through said nipple.

2. In a device as defined in claim 1, and further characterized in that said last named valve means includes a needle valve projecting into said nipple, and said nipple being provided with a valve seat for said needle to receive the same around the outlet port of said nipple.

3. In a device as defined in claim 1, and further characterized in that said last named valve means includes a rotatable control member connected to said extension, and a stop element on said casing to limit rotation of said member, and to permit rotation of said nipple to open and close said last named valve.

4. In a device as set forth in claim 3, and wherein said stop element comprises an air vent.

5. In a device as set forth in claim 3, and

6

wherein said nipple and casing are provided with correlated indicia to indicate the open and shut position of said last named stop means.

6. In an infant nursing device, the improvement comprising the combination of a casing adapted to be applied to the open neck of a nursing bottle containing a liquid food; a non-collapsible nipple connected to said casing; an extension on said nipple adapted to project into said bottle but terminating marginally inwardly of said open neck, and having a longitudinal passageway therethrough and through said nipple; and valve means, communicating with said passageway, being eccentrically mounted and weighted by a ball-check valve element on said extension adjacent said open neck in a manner such that the valve will be submerged in said liquid food when said bottle is up-ended and will remain so submerged until said bottle has been substantially completely emptied.

STEPHEN BARACATE.
